UNITED STATES PATENT OFFICE

170,034

SPOTLIGHT OR SIMILAR ARTICLE

Philip G. Stone, Newark, N. J.

Application December 27, 1952, Serial No. 22,892

Term of patent 14 years

(Cl. D48—20)

To all whom it may concern:

Be it known that I, Philip G. Stone, a citizen of the United States, residing in the city of Newark, county of Essex, and State of New Jersey, have invented a new, original, and ornamental Design for a Spotlight or Similar Article, of which the following is a specification, reference being had to the accompanying drawing, forming a part hereof.

Fig. 1 is a front elevational view of a spotlight or similar article, showing my new design;

Fig. 2 is a rear elevational view thereof;

Fig. 3 is a top plan view thereof;

Fig. 4 is a left side elevational view thereof;

Fig. 5 is a right side elevational view thereof;
and

Fig. 6 is a bottom plan view thereof.

I claim:
The ornamental design for a spotlight or similar article, as shown.

PHILIP G. STONE.
